UNITED STATES PATENT OFFICE

LARS NORMANN, OF CHICAGO, ILLINOIS, ASSIGNOR TO WESTERN ELECTRIC COMPANY,
INCORPORATED, OF NEW YORK, N. Y., A CORPORATION OF NEW YORK

APPARATUS FOR REMOVING MATERIAL FROM ARTICLES

Application filed April 7, 1930. Serial No. 442,436.

This invention relates to apparatus for removing material from articles, and more particularly to apparatus for removing ends of conductors and excess solder from the terminals of electrical apparatus.

An object of the invention is the provision of a simple and efficient mechanism for processing electrical apparatus.

In accordance with one embodiment, the invention contemplates the provision of mechanism for removing the short ends of wires from the terminals of electrical apparatus to which the wires have been soldered wherein the terminals having the wire ends soldered thereto are immersed in a soldering bath and lifted therefrom to a predetermined height against the action of a spring whereupon the energy stored in the springs is effective and is aided by weights to move the apparatus rapidly into engagement with a stationary member to arrest the movement of the apparatus and throw the excess molten solder and the wire ends from the terminals.

Other objects will be more apparent from the following detailed description, when considered in connection with the accompanying drawing, wherein

Fig. 1 is a top plan view of the apparatus;

Fig. 2 is a vertical sectional view taken along the line 2—2 of Fig. 1, and

Fig. 3 is a fragmentary sectional view taken along the line 3—3 of Fig. 2.

Referring now to the drawing wherein like numerals have been employed to designate similar parts throughout the various figures, numeral 10 designates a common base upon which is mounted a heating unit 11. A tank 12 of any desired formation is disposed in the heating unit 11 (Fig. 2), so that a fluid 13, disposed in the tank may have its level substantially flush with the upper surface of the heating unit. A vertically extending partition 14 disposed in the tank 12 and extending the full length thereof is parallel with the front wall of the tank so as to provide a compartment 14 for a purpose hereinafter described.

An article supporting unit indicated generally at 16 consists of a U-shaped frame 17, the ends of which are pivotally mounted at

18 upon vertically extending supporting brackets 19 which are rigidly mounted upon the base 10 at spaced positions. The arm portions of the frame 17 have cam blocks 21 mounted thereupon at positions equally spaced from the ends thereof. The arm portions also have weights 22 and hammers or striking members 23 disposed thereupon at equally spaced positions from the cam blocks 21. The bar or connecting portion of the frame 17 has article supporting members 24 slidably and adjustably mounted thereupon and arranged to be held in predetermined positions by spring actuated locking pins 25 which are receivable in any of a plurality of aligned apertures 26 in the bar or connecting member of the frame. The article supporting members 24 consist of downwardly projecting portions 27 provided with inwardly extending supporting flanges 28, 70 and inwardly extending retaining flanges 29, the retaining flanges having resilient members 30 disposed therebeneath for frictionally holding an article in engagement with the supporting flanges 28. The article shown in this form of the apparatus is a terminal block 33 having a plurality of terminals 34 carried by the central plate thereof. Resilient, or spring members 35 have their upper ends fixed to the outer portions of the 80 bar or connecting portion of the frame 17, while their lower ends are fixed to lugs mounted upon the base 10.

An actuating unit indicated generally at 36 consists of vertically extending fork-shaped bearing members 37 and 38 for rotatably supporting a horizontally disposed cam shaft 39. Frame actuating cams 40 are rigidly mounted upon the shaft 39 and disposed between the forked ends of each of the 90 bearing members 37 and 38. A bearing bracket 42 is mounted upon the bearing member 37 for rotatably receiving the adjacent end of the shaft 39 upon which is mounted a hand lever 43.

The innermost forked portions of the bearing members 37 and 38 are arranged to support movable anvils or abutting members 44. A dovetail connection is preferably provided between the anvils 44 and the inner- 100

most forked portions of the bearing members. Arms 45 which extend downwardly and inwardly are integral with the anvils 44 and are provided with cam rollers 46 adjacent to the outer ends thereof which are receivable in grooves 47 of anvil actuating cams 48. The cams 48 are disposed concentric with the shaft 39 and fixed thereto at positions adjacent the anvils 44.

10 In preparing the apparatus for operation, the fluid 13 which is preferably a soldering bath, is heated to a predetermined temperature by the heating unit 11. The article or terminal block 33 is disposed in place so that the horizontal portion thereof will rest upon the flanges 28 of the article supporting members 24 and the vertical portion thereof disposed in general alignment with the compartment 15 of the tank 12. While in this position (Fig. 2), the shaft 39 is rotated in a counterclockwise direction by the aid of the crank 43, thus allowing the cam blocks 21 to ride upon lowering surfaces 50 of the cams 40 so as to allow the frame 17 to move about its pivots 18 and move the article supporting members 24 together with the article 33 downwardly. At the extremity of the downward movement of the frame 17 the vertical portion of the article extends into the compartment 15, while the lower portions of the terminals 34 are immersed in the fluid or soldering bath 13.

15 The lower portions of the terminals 34 are held in the bath for a predetermined period of time during the positioning of the surfaces 51 in engagement with the cam blocks 22. While in this position the solder upon the terminals will be liquefied, thus loosening the wire ends from the terminals. As the cam blocks 21 ride upon lifting surfaces 52 of the cams 40, the frame 17, together with the members carried thereby will again be raised upwardly to a predetermined position. At this position the anvils or abutting members 44 are moved outwardly through the actuation of the cams 48 and their engagement with the pins 46 so as to position the anvils beneath the hammers 23. When the lifting surfaces 52 of the cams 40 are moved free of the cam blocks 21, the frame, together with the members carried thereby, will be drawn downwardly, about the pivots 18, by the springs 33 aided by the weights 22 so that the hammers 23 will be rapidly moved into abutting engagement with the anvils 44, and held against rebounding by the weights, thus jarring the liquefied solder together with the wire portions free of the lower terminals and into the fluid or soldering bath. To assure an efficient operation, the rotation of the shaft is stopped immediately after the cam blocks 21 are released by the cams 40, allowing the cam blocks to drop into the cutaway portions of the cams.

20 The terminal block 33 may then be removed and again positioned between the article

supporting members 24 so that the other ends of the terminals 34 may be treated to remove the solder and wire portions therefrom.

25 During this operation, the vertical portion of the terminal block 33 extends into the compartment 15 free of the soldering bath, while the lowermost terminals are immersed in the bath, held a predetermined period of time, so as to liquefy the solder thereupon, and raised to a position above the bath. During the 75 raising of the terminal block 33 above the bath, the anvils are moved outwardly into general alignment with the hammers so as to abruptly stop the downward movement of the terminal block, when the frame 17 is released by the cams 40, and jar the solder and wire portions therefrom. By jarring the solder from the terminals in this manner, the solder which was originally upon the terminals will be salvaged, thus obviating the necessity of adding additional solder to the bath. Owing to the fact that the wires are lighter than the bath they will float upon the surface of the bath and be readily removed therefrom. The feature of salvaging the solder which was originally upon the terminals decreases the expense of operation.

30 Even though the shaft 39 is rotated manually, it is obvious that it may be rotated by any suitable power means. Furthermore, the cams 40 may be of suitable contour that the shaft may be rotated continuously, allowing the frame to rest in its movement so as to allow the solid solder upon the terminals to liquefy, to allow the removal of the terminal block 33 and the insertion of another terminal block.

35 Although this invention has been described in connection with an apparatus for reconditioning terminal blocks of an illustrated 105 construction, it is to be understood that the invention is capable of many other applications without departing from the spirit and scope of the invention.

40 What is claimed is:

45 1. In an apparatus for removing material from an article, a bath for liquefying a portion of the material, means for moving the article into and out of said bath, and means whereby the material remaining upon the 110 article may be jarred free thereof.

50 2. In an apparatus for removing material from an article, a supporting member for receiving an article, means for loosening the material upon said article, means for moving said article supporting member whereby the article may be moved into association with said material loosening means, and means associated with said article moving means for imparting a jarring movement to said article 115 whereby the material may be thrown free thereof.

55 3. In an apparatus for removing material from an article, a bath, an article supporting member, means for moving said article sup-

110

- porting member whereby the article may be immersed in said bath, for removing the article from said bath and for releasing said article supporting means whereby said article supporting means and the article may be moved in one direction, and means for stopping the movement of said article supporting means and the article whereby the material may be thrown free of the article.
4. In an apparatus for removing material from an article, a frame, means for pivotally supporting said frame, means movably carried by said frame for supporting articles of various sizes, a bath, means disposed in operative relation with said frame for imparting movement thereto whereby the article may be moved into said bath, moved free of said bath and for freeing said frame whereby it may be moved toward said bath, and abutting means adapted to stop the movement of said frame at a predetermined position.
5. In an apparatus for removing material from an article, a pivotal frame, means for supporting an article carried by said frame, means for liquefying material on the article, means for moving the frame for moving the article into and out of association with said material liquefying means, a hammer member carried by said pivotal frame, and an abutting member adapted to be moved into general alignment with said hammer member, said frame moving means being arranged to free said frame whereby the frame may be moved for moving the hammer member into abutting engagement with said abutting member for jarring the material from the article.
6. In an apparatus for removing material from an article, a support for the article, a bath for liquefying the material upon the article, and means for thereafter subjecting the support to a sudden impact for jarring the material free of the article.
7. In an apparatus for removing material from an article, a frame, means carried by said frame for supporting the article, a bath, means whereby said frame may be moved for moving the article into said bath, for moving the article out of said bath and for releasing said frame, a stop member, and means for moving said stop member free of the path of said frame during the movement thereof to move the article into said bath and for moving said stop member into the path of said frame after the article has been removed from said bath for stopping the movement of said frame when released.
8. In an apparatus for removing material from an article, a frame, means carried by said frame for supporting the article, a bath, means whereby said frame may be moved for moving the article into said bath, for moving the article out of said bath and for releasing said frame, a stop member, means for moving said stop member free of the path of said

frame during the movement thereof to move the article into said bath and for moving said stop member into the path of said frame after the article has been removed from said bath for stopping the movement of said frame 70 when released, and means for urging the frame into abutting engagement with said stop member.

9. In an apparatus for removing wires from terminals which are soldered thereto, a support for the terminals, means for liquefying the solder, and means for thereafter subjecting the support to a sudden impact for jarring the liquefied solder and wires from the terminals.

10. In an apparatus for removing material from an article, a bath, a frame for supporting an article, means whereby the frame may be moved for moving the article into and out of said bath, and means for jarring said frame for freeing the material from the article.

In witness whereof, I hereunto subscribe my name this 28th day of Mar. A. D., 1930.
